(57) **CLAIM**

The ornamental design for a nebulizer compressor, as shown and described.

DESCRIPTION

FIG. 1 is a front, top, and right side perspective view of a first embodiment of a nebulizer compressor showing our new design;

FIG. 2 is a front, bottom, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front, top, and right side perspective view of a second embodiment of a nebulizer compressor showing our design;

FIG. 10 is a front, bottom, and left side perspective view thereof;

FIG. 11 is a front view thereof;

FIG. 12 is a rear view thereof;

FIG. 13 is a top view thereof;

FIG. 14 is a bottom view thereof;

FIG. 15 is a right side view thereof; and,

FIG. 16 is a left side view thereof.

1 Claim, 16 Drawing Sheets
